PRINTING PRESS

Walter J. Hanson, Port Chester, N. Y., assignor
to Pitney-Bowes Postage Meter Co., Stamford,
Conn., a corporation of Delaware

Application May 27, 1942, Serial No. 444,635

2 Claims. (Cl. 101—297)

This invention relates to a printing press which is particularly adapted for the printing of postage impressions upon letters.

It is one object of the invention to provide yieldable spring pressure means for the platen member of a printing press, whereby printing pressure may be maintained under spring control and whereby articles varying in thickness may be printed.

It is another object of the invention to provide an improved form of pressure applying means for effecting movement of the platen to a printing position.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a sectional view through a portion of a letter printing machine, showing the platen control mechanism in elevation;

Fig. 2 is a plan view of the mechanism shown in Fig. 1;

Fig. 3 is a view similar to Fig. 1 showing the platen in a printing position with a letter of normal weight impinged between the platen and printing die; and

Fig. 4 is a view similar to Fig. 3 with a letter of maximum weight impinged between the platen and printing die.

Referring to the drawings in detail, a printing die 10 is mounted in a stationary position within the machine frame 11, and includes the usual postal indicia and value die surface for the printing of postage impressions upon letters, such as provided in known postage printing or metered mail machines.

Directly beneath the printing die 10 is a platen 12, which generally comprises a flexible pad 13, supported in a suitable frame 14. Said frame 14 is pivotally mounted at 14a upon one end of a lever 15, said lever being pivotally mounted upon a suitable shaft 16 supported by the frame structure 11. A roller 17, having an annular groove 18 therein, is rotatably supported by the lever 15 beneath the platen 12.

Another lever 19 is pivotally mounted upon a

suitable shaft 21 and has a projecting lug 20 which is normally urged against a stop 22 by means of a heavy spring 23. The spring 23 has one end anchored to an upwardly extending arm 24 of the lever 19, and the opposite end thereof anchored to an eye bolt 25, which bolt is adjustably mounted in the rear wall 11a of the frame 11. A roller 26, having an annular groove 27 therein, is rotatably mounted at one end of the lever 19 beneath the platen 12.

A power shaft 28, supported by the frame 11, has a manually operable handle 29 secured to one end thereof, as best shown in Fig. 2. A short lever 31 is also fixed to the shaft 28 and extends downwardly therefrom, when the handle is in its normal home position, such as in Fig. 1.

Associated with the lever 31 is an operating bar 32, which bar has a wedge or cam shaped forward end 33 normally supported within the annular grooved portions 18 and 27 of the rollers 17 and 26 respectively. The opposite end of said bar 32 has an elongated slot 33 therein and is normally supported on a rivet stud 34, projecting from the lower end of the lever 31. It will thus be noted that the construction as described, provides for a floating cam or wedge element 33.

A full stroke ratchet 35 is also fixed to the power shaft 28, as shown in Figs. 2 and 3, and has a pawl 36 cooperating therewith to assure the full stroke of the handle 29, both forwardly and rearwardly. By means of a spring 37 having one end anchored to an arm 38, extending from ratchet member 35, the handle 29 is adapted to be returned after each forward power stroke. The platen is returned after a printing operation by means of a spring 41.

Upon rotating the power shaft 28, by pulling the handle 29 in the direction of the arrow, Fig. 2, the rivet stud 34 moves along the slot 33 in bar 32, and upon engagement with the outer end 33a thereof, will effect movement of said bar 32 rearwardly or to the right, as shown in Figs. 1, 3 and 4. During said rearward movement of the bar 32, the wedge shaped portion 33 will move upwardly over the grooved roller 27 to drive the platen upward and effect impingement of a previously inserted letter L between the platen 12 and the printing die 10. Further movement of the bar 32 will cause the wedge surface 33a of the wedge shaped end 33 to be drawn along the groove 27 of roller 26, thereby effecting a substantially vertical rise of the wedge portion of the lever 32 and roller 17. Contact having previously been made between the letter L and the

printing die 10, pressure is effected as the result of the wedging force acting upon the rollers 17 and 26 against the tension of the spring 23. By means of this force, the desired pressure is provided to produce a clear impression upon the letter from the printing die, and the force is obtained by a comparatively light power stroke or pull of the handle 29.

The effect of the spring tension on lever 19 to produce the force for the printing operation also serves to provide yieldability when letters heavier than the average one ounce weight letters are inserted. In Fig. 4 for example, where a letter of maximum thickness is shown, it will be noted that the lever 19 has yielded beyond the point shown in Fig. 3, where an average weight letter is shown.

Having described the invention, what is claimed is:

1. In a printing press, a stationary printing die, a movable platen, a movable member con-

nected with said platen and having a roller mounted thereon, a spring controlled movable member having a roller mounted thereon, a wedge movable between each of said rollers including means to move said wedge during a printing cycle of operation, whereby the platen is raised to move an article thereon into engagement with the printing die, and whereby printing pressure is applied under control of the spring.

2. In a printing press, a stationary printing die, a movable platen, a rocker lever connected with said platen and having a roller mounted thereon, a spring controlled rocker lever having a roller mounted thereon, a wedge movable between each of said rollers including means to move said wedge during a printing cycle of operation, whereby the platen is raised to move an article thereon into engagement with the printing die, and whereby printing pressure is applied under control of the spring.

WALTER J. HANSON.
